Primary Examiner — Bridget L Eland(74) *Attorney, Agent, or Firm* — Pearne & Gordon LLP(57) **CLAIM**

The ornamental design for a cellular phone, as shown and described.

DESCRIPTION

FIG. 1 is a front view of my new invention;

FIG. 2 is a rear view thereof;

FIG. 3 is a left view thereof;

FIG. 4 is a top view thereof;

FIG. 5 is a right view thereof; and,

FIG. 6 is a bottom view thereof.

The broken lines shown within the claimed design that are immediately adjacent to the claim represent the bounds of the claim while all other broken lines, including the broken lines showing the three icons in FIG. 1 and the indicia in FIG. 2, are directed to environment; the broken lines form no part of the claimed design.

1 Claim, 3 Drawing Sheets(56)
